UNITED STATES PATENT OFFICE

2,486,588

LIQUID COOLER

Clem A. Childers, Jr., Johnstown, Pa., assignor to
 The National Radiator Company, Johnstown,
 Pa., a corporation of Maryland

Application October 26, 1945, Serial No. 624,688

2 Claims. (Cl. 257—137)

1

The invention relates to liquid coolers of the type used for reducing the temperature of liquids, such as water that is received from and supplied to the cooling jacket chambers of internal combustion engines, as for example Diesel engines, although the invention may be used for cooling other liquids such as oil and also for condensing vapors.

The object of the invention, generally stated, is to so improve the construction of such coolers that their efficiency is increased and their cost of manufacture reduced.

Specific objects are to provide a cooler formed of a plurality of integrally cast units that are constructed alike and which may be variously arranged in different numbers efficiently to accomplish desired cooling under the conditions of intended service, and to provide a cooler in which the cooling medium, which is usually air, is efficiently used with low power requirements.

The invention is illustrated in the accompanying drawings, of which Fig. 1 is a side view of the cooler; Fig. 2 a left end or face view thereof; Fig. 3 a plan view; Fig. 4 a plan view to enlarged scale of one of the like units through which liquid is circulated; Fig. 5 a vertical longitudinal sectional view taken on the line V—V of Fig. 4; Figs. 6 and 7 transverse sectional views taken on the lines VI—VI and VII—VII, respectively, of Fig. 4; and Fig. 8 a plan view of a connection detail.

The cooler comprises a plurality of like units 1 which are positioned horizontally one on top of the other to form a vertical tier, there being, as shown in Figs. 1 and 2, sixteen of such units used to form the cooler here illustrated, although any desired number of these units may be used. Each unit is an integral casting, preferably made of cast iron, comprising a pair of tubes which lie in a horizontal plane, one behind the other, and a single header at each end of the tubes which communicates with them and with the header or headers of vertically adjacent units. At one side of the vertical tier of units there is a box-like casing 2 which is connected to the periphery of the units in a manner presently to be explained, and within the casing there is a power-driven blower 3 for causing a current of cooling air to flow horizontally around the cooling tubes of the units.

The preferred construction of the units is illustrated in Figs. 4—7. As there shown, each consists of two tubes 5 and 6, both of which are connected at one end to a header 7 and at their other end to a like header 8, each header being pro-

2

vided with passages that place it in communication with both tubes. As shown in Fig. 6, the top and bottom exterior surfaces of each tube are of airfoil section in shape to effect smooth passage of the cooling air over the tubes, and the tops and bottoms of each tube are provided with heat radiating vanes 9 which lie in vertical planes and preferably do not extend beyond the ends of the tube. The vanes, which are cast integrally with the tubes, are tapered gradually from their juncture with the tube walls to their outer edges, and are uniformly spaced from each other horizontally. The top and bottom vanes 9 at the left end of the unit, as seen in Figs. 4 and 5, are closer to header 7 by a distance equal to one-half of the uniform spacing of the vanes than are the end vanes to header 8 at the right end of the tube. By so positioning the vanes on the tubes alternate units 1 may have their headers 7 at the left and their headers 8 at the right of the tier of units, as shown in Fig. 2, and the vanes of each unit will be midway between and overlap those of each adjacent unit. This construction and arrangement of heat radiating fins materially increases the efficiency of the cooler.

As has been stated headers 7 and 8 are alike. Each is provided with a central bore or passage 15 which affords top and bottom openings for placing it in communication with headers of adjacent units, and at each of its sides each header is provided with a chamber 16 to afford free communication between the central passage 15 of the header and the interiors of tubes 5 and 6. Between the top and bottom walls of the headers there are strengthening posts 17. Adjacent to the ends of the adjoining tubes the top and bottom of each header is provided with vertical flanges 18 whose top and bottom faces lie substantially in the planes of the outer edges of the bosses which form the central opening 15 through the header. These flanges form vertical walls at the outer ends of the tubes to prevent lateral flow and eddying of the cooling air that is applied horizontally around the tubes.

Referring now to the assemblage of units to form a tier thereof such as shown in Figs. 1 and 2, it is frequently desirable to cause liquid to flow through a plurality of units from one to the other side of the cooler, and in a circuitous path from its bottom to its top. For this purpose, horizontal partitions are placed between some of the adjacently disposed headers at each side of the cooler, the number and arrangement of such partitions depending upon the number of

units through which it is desired simultaneously to cause fluid to flow at different levels of the headers. In the cooler shown in the drawings the units are arranged in groups of two so that liquid flows simultaneously through alternating pairs of units. The construction and arrangement of partitions to effect this particular flow of water or other liquid will now be explained.

As shown in section at the lower right-hand portion of Fig. 2, an open cylindrical nipple 20 is positioned within the adjacent bores of the headers of the two lowermost units, which nipple forms a seal against the escape of liquid between the units and a passage for the flow of liquid from the header of the lowest to the header of the next unit. In the bores of the adjacent headers of the second and third units from the bottom of the cooler there is a like nipple 21 provided with a horizontal partition which closes communication between such units at the right side of the cooler. Thus liquid is caused to flow from right to left simultaneously through the two bottom units. Like closed or blind nipples are placed between the headers at the right and left side of the cooler at the places indicated at 21, the arrangement being such that liquid which enters the cooler at the lower right-hand corner flows simultaneously from right to left through pairs of units from the bottom to the top of the cooler.

At its lower right-hand corner the cooler is provided with an inlet pipe 25 extending from a supply pump, and at its upper right-hand corner is provided with an outlet pipe 26 leading to an engine or to some other instrumentality with which the cooler is used. At their right-hand ends the outer bores of the headers of the top and bottom units are threaded to form such connections, and at their left-hand ends the like headers of the same units are similarly threaded to receive closure plugs 28. The several units which constitute the tier are firmly bound together by rods 29 which extend through the outer corners of the headers, as seen in Fig. 1.

The box-like casing which extends from the rear of the tier of cooling units has a top wall 30, a bottom wall 31, side walls 32, and an end wall 34 which is provided with a central opening of the diameter required to receive the blades of blower 3 which are suitably encased in a protecting screen 35. For connecting the casing to the tier of cooling units, each header 7 and 8 is provided at its top and bottom with vertical flanges 40, Figs. 4 and 5 that extend parallel with the vertical plane of the cooler. The horizontal meeting faces of these flanges are provided with semi-cylindrical grooves 41 that form cylindrical openings adapted to receive the shanks of bolts 42 (Fig. 8) whose heads are engaged by the flanges 40 of adjacent headers. The end of each side wall 32 of the casing is provided with a lateral flange 50, as shown in Figs. 4 and 8, which in turn is provided with openings 51 to receive bolts 42, the casing being firmly connected to the headers by nuts 43 which engage the projecting ends of the bolts. The position of side walls 32 and their lateral flanges 50 with relation to flanges 40 is shown in Fig. 4, the connecting bolts 42 being there omitted. The side walls 32 of the casing lie in the vertical plane of flanges 40 of the headers so that the cooling air supplied by the blower has a smooth uninterrupted path of flow to and

around the tubes of the vertical tier of cooling units.

The entire cooler may be connected to and supported by a pair of channels 45 which extend from beneath the tier of cooling units rearwardly beyond casing 2. On the rearwardly projecting ends of these channels there is an A-frame having inclined side members 46 whose lower ends are connected to the upper flanges of the channels, and having a horizontal brace 47 extending between and connected at its ends to the side members 46 for strengthening the frame. On the top of this frame there are bearings 48 for the drive shaft 49 of blower 3, and the frame may also support other instrumentalities for circulating liquid through the cooling units.

According to the provisions of the patent statutes, I have explained the principle and operation of my invention and have illustrated and described what I now consider to be the best embodiment of it. However, I desire to have it understood that, within the scope of the appended claims, the invention may be practiced otherwise than specifically illustrated and described.

I claim:

1. A liquid cooler comprising a plurality of like horizontally disposed units arranged in a vertical tier, each unit being an integral casting comprising a pair of tubes lying in a horizontal plane and a single header at each end of the tubes having openings at its top and bottom for communicating with adjacent units, the top and bottom of each of said headers being provided with vertical flanges extending parallel with the plane of the cooler and being provided with grooves that mate with those of the like flanges in adjacent units, bolts having heads engaged by said flanges and shanks lying in said grooves, a box-like casing extending rearwardly from a side of said casing and connected to said headers by said bolts, and a blower within said casing.

2. A liquid cooler comprising a plurality of like horizontally disposed units arranged in a vertical tier, each unit being an integral casting comprising a pair of tubes lying in a horizontal plane and a single header at each end of the tubes having openings at its top and bottom for communicating with adjacent units, the top and bottom of each of said headers being provided with vertical flanges adjacent to the ends of the tubes forming walls to prevent lateral flow of air passing around the tubes, a box-like casing having side walls lying in the vertical planes of said flanges connected to the headers of said units, and a blower within said casing.

CLEM A. CHILDERS, JR.
